[57] CLAIM

The ornamental design for a pencil box with stencil lid,
as shown and described.

DESCRIPTION

FIG. 1 is an exploded top view of a pencil box with the
stencil lid showing my new design;

FIG. 2 is an exploded side elevational view thereof;

FIG. 3 is a left end elevational view thereof;

FIG. 4 is a right end elevational view thereof; and

FIG. 5 is a perspective view of the pencil box, the lid
removed for convenience of illustration.

FIG. 1.

FIG. 2.

FIG. 3.

FIG. 4.

FIG. 5.
